CLAIM

The ornamental design for a tire, as shown and described.

DESCRIPTION

FIG. 1 is a front right perspective view of a tire showing our new design, the design repeated about the circumference of the tire;

FIG. 2 is a front elevation view thereof, the design repeated about the circumference of the tire;

FIG. 3 is a right elevation view thereof, it being understood that the left elevation view is identical thereto;

FIG. 4 is a front right perspective close-up detailed view of the shoulder of the tire; and,

FIG. 5 is a partial sectional view taken along line 5-5 in FIG. 2.
